United States Patent Office.

HENRY DAVIS, OF A BINGDON, ILLINOIS.

Letters Patent No. 61,521, dated January 29, 1867.

IMPROVED SELF-ADJUSTING TRESTLE.

The Schedule referred to in these Letters Patent and making part of the same.

TO ALL TO WHOM IT MAY CONCERN:

Be it known that I, HENRY DAVIS, of the city of Abingdon, in the county of Knox, in the State of Illinois, have invented a new and useful machine for the use of builders, plasterers, and painters, being a Self-Adjusting Trestle, to be used instead of erecting scaffolding or benches, said machine being known as "Davis's Self-Adjusting Trestle;" and I do hereby declare that the following is a full, clear, and exact description of the construction and operation of the same, reference being had to the annexed drawings, making a part of this specification, in which—

Figure 1 is the trestle as extended.

Figure 2 is the trestle nearly closed.

Figure 3 is the brace.

Figure 4 is the legs and standard.

Figure 5, the extension bands.

The trestle is made in two parts, which correspond with each other. Take either of these parts, let the legs and standard be at the left hand, draw back the legs to the left hand perpendicularly to the standard, tighten the screw *a*, raise the end of the brace *b*, and adjust it to the extension-board at the screw *c*, tighten screw *d*. Look at the hook *e* at the end of the extension-board, and set it so that the top part of it points towards you. Then take the other part of the trestle, and put that together in the same manner, setting the hook at the end of the extension-board so that the top part of it points from you. Then lay one hook on the top of one extension-board and the other hook on the top of the other extension-board; push the two parts of the trestle together till the hooks touch the standards. The trestle then will be in working order, or ready to receive the boards for the scaffolding. Two of these trestles will of course be required for work, sometimes three, depending upon the length the scaffolding or bench is required. The scaffolding, as the trestle thus stands, will be about three feet high. To extend the trestle, it is only necessary to draw it apart by the standards. It can be extended to about thirteen feet or more, depending of course upon the length of the extension-boards. When extended to its full length, take the loose bolt which is in the leg of the trestle, and pass it through the holes near the ends of the extension-boards, and tighten it, which keeps the extension-boards in their proper places in case of removing or drawing the trestle when extended. The trestle can be raised to about six feet, or double the height of the standards. To raise it, loosen the bolts *a* and *d*, and raise the extension-boards to the height desired, inserting the pins attached to the legs in one of the holes of the standards. In case it is desired that the scaffolding should be lower than about three feet, which is often required in plastering and painting, it can be made lower by the following mode: Separate the two parts of the trestle by lifting the ends of the extension-boards, thus unhooking them; loosen the bolts *a* and *d*, and detach the brace from bolt *c*; then turn the brace and legs back over the short end of the extension-board, bringing the end of the brace back to bolt *c* and attach it; bring the standard perpendicularly to the legs, place the pin in the standard at the desired height, and tighten the bolts *a* and *d*. Then reverse the hook by turning it upside down. Put the other part of the trestle in the same position by a similar process, and lay the hooks over the extension-boards, as before mentioned. For some purposes, such as painting, building, carpenter-work, &c., it is not generally necessary to have an extension-trestle, and in that case one of the extension-boards is omitted, and the other is attached permanently to the standards.

What I claim as my invention, and desire to secure by Letters Patent, is—

The construction and arrangement of a trestle in the manner and for the purpose herein described.

HENRY DAVIS.
